J. L. FLANNERY

EMBROIDERY STILETTO

Filed March 21, 1925

Inventor:

John L. Flannery,
By his wife, Christine Flannery,
Attest,

UNITED STATES PATENT OFFICE.

JOHN L. FLANNERY, OF CHICAGO, ILLINOIS, ASSIGNOR TO THE BOYE NEEDLE COMPANY, OF CHICAGO, ILLINOIS, A CORPORATION OF ILLINOIS.

EMBROIDERY STILETTO.

Application filed March 21, 1925. Serial No. 17,250.

To all whom it may concern:

Be it known that I, JOHN L. FLANNERY, a citizen of the United States, residing at Chicago, in the county of Cook and State of Illinois, have invented a new and useful Improvement in Embroidery Stilettos, of which the following is a specification.

This invention relates particularly to a device for use in embroidery work, such device being of the type employing an adjustable needle.

The primary object is to provide a very simple, cheap and effective device of this type.

The invention is illustrated in its preferred embodiment in the accompanying drawing, in which—

Fig. 1 represents an elevational view of the improved device, the dotted lines illustrating a change in the adjustment of the needle; Fig. 2, a longitudinal sectional view of the device; Fig. 3, a perspective view of the combined sheath and gage employed; and Fig. 4, a section taken as indicated at line 4 of Fig. 2.

The improved device comprises a handle 1 which may be of wood, or other suitable material, preferably non-metallic; a combined sheath and gage 2 fixedly mounted in the handle 1; and an adjustable pointed stem, or needle, 3.

The handle 1 is provided with a longitudinal bore 1^a within which is securely held a tubular shank 2^a of the member 2.

The member 2 preferably is formed by rolling a strip of sheet metal into tubular form. That portion of the metal which projects from the socket, or bore, 1^a of the handle is cut away throughout the larger portion of its circumference, leaving a standard 2^b. The extremity of the strip is formed into a ring 2^c which is disposed at right angles to the axis of the member 2.

One wall of the tubular shank 2^a of the member 2 is provided with a longitudinal slot 4 which registers with a slot 4^a in the tubular portion of the handle 1.

The needle, or shaft, 3, is provided with a long tapered extremity 3^a. The base end 50 of the member 3 is provided with a threaded transverse perforation 3^b which receives a set screw 5 which may slide freely in the

slots 4 and 4^a. The shaft 3 may be fixed in any desired position by turning the set screw in until its inner end bears against the adjacent inner wall of the tubular shank 2^a. The pointed extremity of the shaft, or needle, 3, extends through the ring 2^c, which may serve as a gage. That is, the point may be allowed to project a suitable distance beyond the ring to enable a perforation of the desired size to be made in the fabric being embroidered.

When the device is not in use, the needle 3 may be sheathed by loosening the set screw and dropping the needle to the bottom of the bore in the handle, and then tightening the set screw. When this is done, the point of the needle will be sheathed within the ring 2^c.

The improved device is extremely simple, may be cheaply manufactured, and is thoroughly adapted to its purpose. If desired, the tubular shank 2^a of the member 2 may be left slightly open at the line 2^d where the longitudinal edges of the strip meet when the tube is formed; and when the shank is inserted, the tube may be compressed somewhat so that it will, by the resilience of the metal, be firmly held within the socket 1^a of the handle.

What I regard as new, and desire to secure by Letters Patent, is:

1. A device of the character set forth, comprising a handle having one end provided with a bore, a combined sheath and gage comprising a member having a tubular shank fitted into the bore of said handle and having a projecting shank equipped with a transverse ring, said tubular shank and the tubular portion of said handle being provided with a slot, a pointed shaft having its base portion received within the tubular shank of said combined sheath and gage and having its pointed portion adapted to work through said ring, and a set screw connected with the base portion of said shaft and adapted to be adjusted in said slot.

2. A device of the character set forth, comprising a handle having one end provided with a socket, one wall of said socket being provided with a slot, a combined sheath and gage comprising a sheet metal strip rolled into tubular form and secured in said socket

and having a slot registering with said first-named slot, said combined sheath and gage having a projecting stem formed by cutting away the metal and having a transversely disposed ring at the extremity of said stem, a pointed shaft having its base portion received by the tubular shank of said com-

bined sheath and gage and having its pointed portion adapted to be extended through said ring, and a clamping screw connected with the base portion of said shaft and adapted to be adjusted in said slots. ¹⁰

JOHN L. FLANNERY.
